(57) **CLAIM**

The ornamental design for a dental handpiece bur release accessory, as shown and described.

DESCRIPTION

FIG. 1 is a perspective view of a dental handpiece bur release accessory showing my new invention;

FIG. 2 is a side view thereof.

FIG. 3 is an opposite side view thereof.

FIG. 4 is an end view thereof.

FIG. 5 is an opposite end view thereof.

FIG. 6 is a top view thereof.

FIG. 7 is a bottom view thereof; and,

FIG. 8 is another perspective view thereof, showing the dental handpiece bur release accessory in use.

The broken lines shown in FIG. 8 illustrate environment and form no part of the claimed design.
